FLOWING DEVICE FOR WELLS.

1,414,402.

Specification of Letters Patent. Patented May 2, 1922.

Application filed March 27, 1922. Serial No. 546,948.

To all whom it may concern:

Be it known that we, LOUES FRIEDMAN and DAVID WALLACE, citizens of the United States, and residents, respectively, of Muncie, in the county of Delaware and State of Indiana, and Tulsa, in the county of Tulsa and State of Oklahoma, have invented certain new and useful Improvements in Flowing Devices for Wells, of which the following is a specification.

Our present invention relates generally to flowing devices for wells, and more particularly to devices adapted to promote the flow of oil from oil wells where insufficient pressure exists to cause flow through the well casing, although our invention is adapted for use in connection with water as well as oil and under the influence of either the natural existing pressures or pressures introduced for the purpose of bringing about the desired operation.

It is a well known fact that particularly in case of oil wells, relatively low pressure will fail to cause flow of oil upwardly through the well casing and it becomes necessary to use means for pumping the oil out of the well involving all of the expensive apparatus commonly incident to pumping operations of this nature and involving waste of what pressure, for instance gas pressure, exists.

Through the use of our improved device we take advantage of the natural gas pressure in forcing the oil as it accumulates in the bottom of a well to flow naturally and continuously throughout flow tubes, and we trap the gas pressure for this purpose, using the same with or without the introduction of additional pressure as may be necessary.

One of the various objects of our invention aims to provide a simple inexpensive device singularly free of valves and other complicated parts, and one which may be readily and easily introduced into a well and removed therefrom.

In the accompanying drawing illustrating our invention and forming a part of this specification,

Figure 1 is a vertical sectional view through our invention illustrating the same in its practical application,

Figure 2 is a detail perspective view of the expansion gasket, and

Figure 3 is a cross section through our improved device taken on line 3—3 of Figure 1.

Referring now to these figures our invention is connected to the lower end of an outflow tube 10, as for instance by means of a coupling sleeve 11, and includes an inner cylindrical barrel 12, attached to the outflow tube 10 by means of the cylindrical coupling 11 the latter of which may be in the form of a swage nipple where for instance an outflow tube is desired of smaller diameter than that of the barrel 12.

The barrel 12 is externally threaded for a considerable distance from its upper end to receive an internally and externally threaded cast ring 13 as well as an expansion gasket 14 between the cast ring 13 and the coupling 11, relatively thin flat washers 15 and 16 being utilized respectively above and below the expansion gasket the latter of which closely interfits the well casing 17 and seals the same at whatever point it is stationed in order to confine gas pressure within the well below the gasket.

Connected to the cast ring 13 by an internally threaded coupling sleeve 18 is the upper externally threaded one of a cylindrical outer shell 19 which surrounds the lower portion of the inner barrel 12 in spaced relation so as to form a chamber between these parts upwardly into which oil and gas are free to flow, the lower end of the shell 19 being preferably threaded on its exterior for the connection of any suitable screening device should the latter be found necessary or desirable, it being noted that the lower end of the barrel 12 depends below the lower end of this shell and is likewise threaded on its exterior at its lower end so that any suitable anchor may be attached thereto should the use of an anchor become necessary or desirable.

Approximately opposite the cast ring 13, the barrel 12 is closed by means of a plug 20 threaded therein, this plug serving for the support of the upper end of one or more pressure tubes 21, the upper threaded ends of which extend upwardly beyond and open above the plug and are externally threaded to receive retaining nuts 22 and are also preferably provided with threaded protecting sleeves 23.

The pressure tubes 21 depend within the barrel 12 and have lower outturned ends 24,

projecting through openings in the barrel and opening into the space between the barrel and the outer shell 19, these lower angular or outturned ends of the pressure tubes 5 being preferably threaded to receive retaining nuts 25 and being thus in position so that oil and gas may enter the lower outer ends thereof and, by virtue of the small cross section of the tubes, enable a comparatively 10 low gas pressure to lift the oil through the tubes where this gas pressure would be insufficient to effect lifting of the oil in the well casing 17 or even in the outflow tube 10 into which the upper ends of the pressure 15 tubes 21 discharge.

In the upward movement of the oil through the outflow tube 10, it may of course be controlled by one or more check valves placed at any suitable points in the length 20 of the tube, and it is obvious that the pressure tubes 21 may be utilized in varying numbers and but a single one employed in instances where the pressure is not sufficient to force the oil upwardly through more than 25 a single tube.

Thus by forcing the flow device provided by our invention downwardly in a well, the gas pressure is trapped below the expansion gasket and collects within the shell 19 along 30 with the oil as the latter seeps from the oil sands upon or slightly above which the flow device is positioned, whereby the oil will be constantly forced by the gas pressure upwardly through the pressure tubes and into 35 the outflow tube and a steady flow of oil and gas brought about in this manner, the gas itself being by virtue of this intimate contact with the oil rendered extremely rich in gasoline which may be subsequently withdrawn 40 in the usual manner of extracting casing head gas.

Where in spite of the presence of the pressure tubes 21 the gas pressure is insufficient to cause the oil to flow, we may utilize a 45 pressure introducing line 26 extending downwardly in the well casing 17 alongside the outflow tube 10 and downwardly through the expansion gasket 14 into the space between the shell 19 and the barrel 12, the 50 lower end of this pressure introducing tube being preferably extended slightly below the lower end of the shell 19 and externally threaded as shown in Figure 1 so as to provide for the ready attachment of an extension thereon either of a perforate or imperforate nature.

The expansion gasket 14 which as above stated is utilized between washers 15 and 16, is preferably of the form best seen by a comparison of Figures 1 and 2, being constructed 60 of soft rubber and having its periphery provided with an annular series of notches or recesses 27 so that it is readily compressible to some extent sufficient to permit it to be

easily introduced into and removed from a 65 well casing as well as to allow it to yield in the presence of blisters or internal protuberances of the well casing.

By thus providing a device whereby the gas may be entrapped in the lower part of a 70 well and caused to flow through a pressure tube or channel the cross section of which is such as to bring about flow in the presence of gas pressure materially less than that required to bring about flow upwardly in the 75 well casing or even in the outflow tube 10, and by providing a device which will in this way insure a steady outflow of oil and gas, we not only greatly increase the recoverable 80 portion of the oil production, but we also do away with the disadvantages of an intermittent flow and collect and discharge the oil as it accumulates so as to avoid dead oil in the bottom of the well.

We claim:

1. A flowing device for oil wells including a cylindrical shell open at its lower end to receive oil and gas therein, and closed at its upper end, an outflow tube having connection with the upper end of the cylindrical shell and by means of which the latter may be lowered into a well casing, a tube supporting barrel within and spaced from the shell, and one or more pressure tubes within the barrel, the lower ends of 90 which open through the barrel and into the shell, and the upper ends of which open into the said outflow tube.

2. A flowing device for wells including a cylindrical shell for introduction within 100 a well casing, having a lower open end, a barrel within and spaced from the shell, having its upper end extended beyond the upper end of the shell, a ring around the barrel to which the upper end of the shell is 105 coupled, an outflow tube coupled to the upwardly projecting end of the barrel, a plug within the upper portion of the barrel, and one or more pressure tubes secured at the lower end thereof through the barrel 110 and opening into the shell and secured at the upper end thereof through the plug of the barrel and opening into the outflow tube.

3. A flowing device for wells including a cylindrical shell for introduction within a 115 well casing, having a lower open end, a barrel within and spaced from the shell, having its upper end extended beyond the upper end of the shell, a ring around the barrel to which the upper end of the shell is coupled, 120 an outflow tube coupled to the upwardly projecting end of the barrel, a plug within the upper portion of the barrel, and one or more pressure tubes secured at the lower end thereof through the barrel and opening 125 into the shell and secured at the upper end thereof through the plug of the barrel and opening into the outflow tube, and an

expansion gasket around the upper portion of the barrel and seated on the ring at the upper end of the shell.

4. A flowing device for wells including a cylindrical shell for insertion within a well casing, open at its lower end, a ring to which the upper end of the shell is coupled, a barrel extending through the shell in spaced relation thereto, having a portion projecting 10 through and above the said ring, an outflow tube connected to the upper end of the barrel, a plug within the upper portion of the barrel, a pressure tube within the barrel having a lower outturned end secured 15 through the wall of the barrel and opening into the space between the barrel and the shell and having its upper end secured through the plug and opening into the said outflow tube.
- 20 5. A flowing device for wells including a cylindrical shell for insertion within a well casing, open at its lower end, a ring to which the upper end of the shell is coupled, a barrel extending through the shell in spaced relation thereto, having a portion projecting 25 through and above the said ring, an outflow tube connected to the upper end of the barrel, a plug within the upper portion of the barrel, a pressure tube within the barrel 30 within the barrel having a lower outturned end secured through the wall of the barrel and opening into the space between the barrel and the shell and having its upper end secured through the plug and opening into the said outflow tube, and an expansion 35

gasket around the upper portion of the barrel seated on the upper ring of the shell.

6. A flowing device for wells including a cylindrical shell open at its lower end, a barrel extending axially through the shell, 40 means connecting the barrel and the shell and closing the upper end of the latter, a flow line into which the upper end of the barrel opens, and a pressure tube within the barrel and connected to the latter adjacent 45 to its opposite ends, the lower end of said tube opening into the shell and the upper end thereof opening into the outflow line.

7. A flowing device for wells, including a cylindrical shell closed at its upper end 50 and open at its lower end to receive pressure therein, a barrel mounted lengthwise through the shell, an outflow line communicating with the upper end of the barrel, and a pressure tube supported within the barrel 55 with its lower end opening into the shell and with its upper end opening into the outflow line.

8. A flowing device for wells including a downwardly opening fluid and pressure receiver insertable in a well casing, having an outflow line connected to its upper closed end, a pressure tube forming the sole means of communication between the interior of said receiver and the said outflow line, and 60 means disposed within and connected to the said receiver for supporting the said tube adjacent to its opposite ends.

LOUES FRIEDMAN.
DAVID WALLACE.
